US0D1101713S

(12) **United States Design Patent** (10) **Patent No.:** **US D1,101,713 S**
(45) **Date of Patent:** **** Nov. 11, 2025**

(54) **WIRELESS COMMUNICATION ADAPTER**

(71) Applicant: **New Audio LLC**, New York, NY (US)

(72) Inventors: **Jonathan Levine**, New York, NY (US); **Thomas C. Wilson**, Brooklyn, NY (US); **Marshall Plummer**, Nashville, TN (US); **Clayton J. Pipkin**, Highland Park, NJ (US); **Zachary James Hellman**, New York, NY (US)

(73) Assignee: **New Audio LLC**, New York, NY (US)

(**) Term: **15 Years**

(21) Appl. No.: **29/875,285**

(22) Filed: **May 2, 2023**

(57) **CLAIM**

The ornamental design for a wireless communication adapter, as shown and described.

DESCRIPTION

FIG. 1 is a top, front perspective view of a wireless communication adapter showing our new design.

FIG. 2 is a front view thereof.

FIG. 3 is a back view thereof.

FIG. 4 is a left side view thereof.

FIG. 5 is a right side view thereof.

FIG. 6 is a top plan view thereof.

FIG. 7 is a bottom plan view thereof.

FIG. 8 is a top, front perspective view of the wireless communication adapter of FIG. 1, shown in an extended state.

FIG. 9 is a front view thereof.

FIG. 10 is a back view thereof.

FIG. 11 is a left side view thereof.

FIG. 12 is a right side view thereof.

FIG. 13 is a top plan view thereof; and,

FIG. 14 is a bottom plan view thereof.

The broken lines depict environment that forms no part of the claimed design.

1 Claim, 14 Drawing Sheets
